UNITED STATES PATENT OFFICE.

ALFRED G. F. KUROWSKI, OF BROOKLYN, NEW YORK, ASSIGNOR TO UNDERWOOD TYPEWRITER COMPANY, OF NEW YORK, N. Y., A CORPORATION OF DELAWARE.

TYPEWRITING MACHINE.

Application filed September 19, 1922. Serial No. 589,064.

To all whom it may concern:

Be it known that I, ALFRED G. F. KUROWSKI, a citizen of the United States, residing in Brooklyn Borough, in the county of

5 Kings, city and State of New York, have invented certain new and useful Improvements in Typewriting Machines, of which the following is a specification.

This invention relates to typewriting machines, and more particularly to typewriting machines especially adapted for writing checks and making a copy on a continuous record-sheet of a part of the matter typed on each check of a series of checks.

10 15 In writing checks it is customary to insert each check in the typewriter and type two lines upon it. The first line consists of the name of the payee and the numerals indicating the amount for which the check

20 25 is drawn, and the second line consists of a statement of the amount for which the check is drawn spelled out in full. It is desirable to keep a condensed record of the checks by copying on a record-sheet the first typewritten line only of each check. With this end in view, there is provided, in addition to the usual ribbon mechanism for writing on the faces of the checks, an auxiliary ribbon mechanism adapted to be moved to and from

30 35 position to cause the ribbon of the said mechanism to be effective to make a copy on the record-sheet of the matter which is being typed on the face of a check. In the illustrated machine, the auxiliary ribbon is lowered into operative position as an incident of the movement of the feed-rollers

40 45 into engagement with the platen, and is automatically withdrawn from operative position by the actuation of the line-spacing lever. Means are provided for locking the ribbon in its withdrawn position. When a check is inserted in the machine, therefore, and the feed-rollers are moved into engagement with the platen, the first line written

50 55 thereafter is copied, through the medium of the auxiliary ribbon, onto the record-sheet, but the second line is written on the check only, due to the fact that the auxiliary ribbon has been withdrawn from operative position by an actuation of the line-spacing

lever. Means are also provided whereby the ribbon may be moved to operative position, if desired, without actuating the feed-roll release lever.

The auxiliary ribbon is carried by spools 55 mounted at the ends of the platen on a swinging frame, and this frame is mounted on a shaft extending from end to end of the carriage. The swinging movements imparted to the ribbon-carrying frame by 60 movement of the line-spacing lever are utilized to produce rotary movements of the spools for feeding the ribbon. Feeding mechanism for this purpose is provided in conjunction with each spool, these mechanisms being effective to feed the ribbon in opposite directions, and controlling means are provided for rendering the ribbon-feeding means for the different spools alternatively and selectively operative. 70

A paper-positioning and guiding frame is provided, having a plate for locating the check in proper position and an auxiliary roll which normally rests upon the platen to guide the record-sheet rearwardly out of 75 the way of the auxiliary ribbon mechanism. This frame is adapted to be swung upwardly to permit the insertion of the record-sheet between the platen and the auxiliary roll, and means are provided whereby upward 80 swinging of the paper-guiding frame will be effective to raise the auxiliary ribbon mechanism above the position to which it is moved by the line-spacing lever, in order to permit the insertion of the record-sheet in 85 the machine without obstruction.

Other features and advantages will hereinafter appear.

In the accompanying drawings,

Figure 1 is a front elevation of a portion 90 of a typewriting machine in which the improvements of the present invention are embodied.

Figure 2 is a plan view of the same.

Figure 3 is a vertical sectional view of 95 the carriage taken near the right end thereof, showing the parts in their normal idle positions.

Figure 4 is a view similar to Figure 3, with the parts in the positions which they 100

will assume after insertion of the record-sheet and check and before the feed-rollers have been moved to active position.

Figure 5 is a vertical section of the carriage, showing the auxiliary ribbon in the position which it will occupy during the writing of the first line of the check.

Figure 6 is a transverse vertical section of the ribbon-spool at the right end of the machine, showing the details of the spool's mounting.

Figure 7 is a sectional view similar to Figures 3 and 4, showing the parts positioned for the introduction of the record-sheet into the machine.

Figure 8 is a diagrammatic view illustrating the ribbon-feed-controlling mechanisms at the opposite ends of the carriage, and the means for reversing the ribbon-feed controlling mechanisms.

Figure 9 is a vertical section through the carriage, showing the paper-guiding frame swung upward to a position where further upward movement will be effective to raise the auxiliary ribbon mechanism.

Figure 10 is a vertical section illustrating the positions of the parts just after the actuation of the line-spacing lever and before it has been returned to normal position.

Figure 11 is a vertical section of the carriage taken beyond the left end of the platen and looking toward the right. The lowered position of the auxiliary ribbon frame is illustrated in full lines and the elevated position is illustrated in broken lines in this view.

The typewriting machine of the present invention is provided with the usual ribbon 1, which is fed back and forth between spools 2 (only one of which is shown) and is threaded through a ribbon-guide 3, to position it behind a type-guide 4 in position to be struck by the types 5 for making an impression on the paper in the machine. A wire paper-guide 6 serves to assist in holding the paper toward the platen. A paper-support 7 may be mounted on the machine frame to assist in positioning checks inserted from the front of the machine. A platen-shaft 8, having a platen 9 thereon, is rotatably mounted in the platen-frame 10 in the usual manner. Paper-feed-rollers 11 are provided for co-operating with the platen in feeding the paper, and these may be moved to operative and inoperative positions by the usual controlling means, which include a paper-release handle 12 fixed to a short shaft 13, which is mounted in the platen-frame, a crank-arm 14 on the shaft 13, and a link 15.

A rock-shaft 16, rotatably mounted in the ends of the platen-frame 10, has plates 17 fixed upon it near its opposite ends. The plates and rock-shaft form an auxiliary ribbon-carrying frame, each plate being provided with ribbon-supporting and guiding means, as follows: Each of the plates 17

carries a bearing 18 in an upper part thereof, in which is mounted a sleeve 19 formed integrally upon a ratchet-wheel 20. A shaft 21 is mounted in the sleeve 19. An angular plate spring 22 is connected to one end of the shaft 21 by a screw 23, and carries at its free end a finger 24, which it presses into frictional engagement with the outside of the sleeve 19 through a hole 25 in the bearing 18 to regulate the movements of the ratchet-wheel 20. A ribbon-spool 26 is rotatably mounted on the shaft 21, being held in position thereon by a nut 27 received on a reduced threaded end 28 of the shaft. A pin 29 on the ratchet-wheel engages in a hole 30 in the ribbon-spool and compels the ratchet-wheel and spool to rotate in unison. The plates 17 extend forwardly to positions slightly in advance of the front of the platen and are there bent substantially at right angles to direct them toward each other, whereby portions 31 are provided extending transversely of the machine. The portions 31 extend inwardly to points slightly beyond the inner walls of the ribbon-spools 26, where they are bent forwardly to provide portions 32, which terminate in upwardly-extending arms 33. Pins 34 are mounted in the arms 33 and the main bodies of the plates 17, and have small spools 35 upon them for guiding the ribbon 36 without unnecessary friction. Inclined slots 37 in the portions 31 of the plates 17 and vertical slots 38 in the portions 32 serve as guides for the ribbon 36.

A spring 39, connected to the platen-frame and to a pin 40 on the rock-shaft 16, tends to swing the rock-shaft, and therefore the auxiliary ribbon-carrying frame, in a counter-clockwise direction, as viewed in Figures 3 and 4. A cam 41, fixed upon the shaft 16, has a wall 42 adapted to be engaged by a finger 43 of a latch 44, to prevent the movement of the auxiliary ribbon mechanism to lowered position whenever it is raised sufficiently to permit the finger of the latch to ride off the high part of the cam 41. The latch 44 is pivoted upon pin 45 on the platen-frame, and its finger 43 is urged toward the cam 41 by a coil spring 46 connected to the latch and to a pin 47 on the platen-frame. A hook 48, pivoted on the latch 44, is held by gravity in engagement with an angular portion 49 of the latch in a position to engage beneath a beak 50 on the link 15 of the feed-roller-controlling mechanism when the link 15 is raised by movement of the paper-releasing handle 12 as an incident of the movement of the feed-rollers away from the platen (see Figure 4). Movement of the handle 12 to restore the feed-rollers to operative position will be effective to draw the hook 48 downward, and thereby to swing the latch 44 about its pivot. This will permit the spring 39 to rotate the rock-shaft 16 and

thus move the auxiliary ribbon mechanism to lowered position. A finger-piece 51 is provided on the latch 44, whereby the latch may be rocked to release the shaft 16 without actuation of the paper-releasing handle 12.

The usual line-spacing lever 52 is pivotally mounted at the left end of the carriage, and is effective to thrust rearwardly a slide 53. The slide 53 carries the usual pawl 54 for engaging the teeth of the ratchet-wheel 55 and moving them to effect line-spacing. The extent of the line-spacing movements is controlled as usual by a slide 56 having a latch 57 upon it for engaging a cam-surface 58 on the pawl 54. The slide 56 is movable to any one of three selected positions by a lever 59 pivoted on the carriage and connected to the slide through links 60 and 61. A plate 62, having slots 63 therein, is slidably mounted on the top of the platen-frame. Screws 64 pass through the slots of the sliding plate 62, and are secured in the platen-frame for holding the plate 62 in position and guiding it in its sliding movements. The sliding plate 62 has a downwardly-bent and rearwardly-turned portion 65 at its rear extremity, which is connected to the rear end of the slide 53 by a pin 66. A coil spring 67 is connected to the portion 65 of the sliding plate 62 and to a lug 68 on the platen-frame, and is effective to move both the sliding plate 62 and the slots 63 forwardly when the line-spacing lever 52 is released by the operator. A cam 69 is formed on the inner edge of the sliding plate 62 and has horizontal and inclined surfaces to engage a pin 70 on the outside of the plate 17 at the left end of the machine, the latter to raise the pin 70 when the plate 62 is moved rearwardly, to rock the plates 17 upwardly and rearwardly.

The auxiliary ribbon-spools and ratchet-wheels, which are mounted on the plates 17, necessarily move rearwardly with the plates, and this rearward movement is utilized for effecting feeding of the ribbon. For this purpose, mechanisms are provided at opposite ends of the machine for co-operating with the ratchet-wheels 20, which are adapted to cause the ribbon to be fed in opposite directions. Since these mechanisms are duplicates, one only will be described. A pawl 71 is rotatable on a stub-shaft 72 mounted in one end of the platen-frame, and its tooth 73 is urged toward the ratchet-wheel 20 by a coil spring 74 connected to the tail of the pawl and to the platen-frame. A pawl 75 is pivoted at 76 upon the plates 17, and has its tooth 77 urged toward the ratchet-wheel 20 by a coil spring 78 connected to an arm 79 of the pawl and to the plates 17. An arm 80 on the pawl 75 overlies the pawl 71, so that, when the pawl 71 is forcibly moved away from operative position, the pawl 75 will be moved away from operative

position also. When the ratchet-wheel is moved bodily with the plate 17, the tooth 73 of the pawl 71 engages a tooth of the ratchet-wheel and holds it substantially stationary, thereby causing the ratchet-wheel to be rotated relatively to the plate 17 and the pawl 75. Upon the return of the plate 17 to lowered position, the pawl 75 will prevent retrograde movement of the ratchet-wheel, and the pawl 71 will slide along the ratchet-wheel and engage a fresh tooth thereof. A controlling lever 81, pivoted at 82 to the platen-frame, has a forward end which overlies the pawl 71 and is adapted to be depressed to move the pawl 71 away from the ratchet-wheel 20.

A shaft 83, mounted in brackets 84 on the platen-frame and having a handle 85, carries angularly-related crank-arms 86 and 87 adjacent the respective levers 81 at the right and left ends of the platen-frame. The lever 81 at the left end of the platen-frame is provided with a notch 88 in its lower cam-surface and a cam-surface 89 at the rear thereof, and the lever 81 at the right end of the platen-frame is provided with a notch 90 in its lower surface and a cam-surface 91 in advance thereof. The crank-arms 86 and 87 carry rollers 92 and 93, respectively, for engaging the levers 81. When either of the rollers 92 or 93 is in position to engage the notch in its lever 81, the tail of that lever will be raised and its forward end depressed to move the ribbon-feeding mechanism which it controls out of operative position. The crank-arms 86 and 87 are so arranged on the shaft 83 that the movement of the roller 93 into the notch 88 will move the roller 92 along the cam-surface 91, and thereby permit the feeding mechanism at the left end of the platen-frame to become operative, and the movement of the roller 92 into the notch 90 will move the roller 93 along the cam-surface 89, and thereby permit the feeding mechanism at the right end of the platen-frame to become operative. Since these mechanisms feed the ribbon in opposite directions, it will be seen that movement of the handle 85 from one to the other of the positions shown in Figure 8 will reverse the direction of the ribbon feed. A paper-positioning frame 94 is mounted on the rock-shaft 16 for swinging movement with relation thereto. This frame carries an auxiliary paper-guiding roller 95 which guides the record-sheet rearwardly and limits the downward swinging movement of the paper-positioning frame by engagement with the platen. A paper-guiding plate 96 is adjustably mounted on the front wall of the frame 94 by screws 97 and nuts 98, which engage in horizontal slots 99 on the frame 94 and in vertical slots 100 formed in ears 101 of the paper-guiding plate 96. The paper-guiding plate has paper-gaging flanges 102

and 103 formed along its upper and left edges, respectively. The frame 94 is provided with a finger-piece 104, by which it may be conveniently swung to a raised position to permit the insertion of the record-sheet in the machine. Pins 105 extend laterally inwardly from the ends of the frame 94 into positions to engage pins 106 on the shaft 16 when the frame 94 is raised and cause the shaft 16 to rotate in unison with the frame 94, thereby raising the auxiliary ribbon mechanism to the position shown in Figure 7. Detents 107, pivoted on short shafts 108 of the platen-frame are pressed by plate springs 109 into engagement with the rear surfaces of the frame 94, and are adapted to be received in rounded notches 110 of the frame to retain it yieldingly in the position of Figure 7.

The operation of the machine is as follows: The parts will normally be in the position shown in Figure 3 with the auxiliary ribbon mechanism in lowered position. The operator lifts the finger-piece 104, raising the parts to the position of Figure 7, inserts the record-sheet, lowers the frame 94, and throws off the feed-rollers preparatory to the insertion of a check in the machine. This brings the parts to the position shown in Figure 4. The handle 12 is then raised to move the feed-rollers into engagement with the platen, and this restores the auxiliary ribbon mechanism to the position shown in Figure 3. The first line is typed on the check, and the auxiliary ribbon is then raised to the position of Figure 10 by actuation of the line-space lever, and is retained in that position by the latch 44. The second line is then typed, the feed-rollers are moved away from the platen, the written check is lifted out of the machine, and a new one is inserted. The feed-rollers are returned into engagement with the platen, and this movement of the feed-rollers is effective again to move the auxiliary ribbon in operative position for the writing of the first line of the second check.

Should it be desired to copy the second line written upon a check, or any other form used as the outside sheet, onto the record-sheet, the platen may be line-spaced through the knobs at its ends without raising the auxiliary ribbon mechanism, or the line-space lever may be operated and the ribbon mechanism may then be lowered to the position of Figure 3 by depressing the finger-piece 51 of the latch 44. The auxiliary ribbon mechanism may also be raised without line-spacing, by lifting the frame 94 sufficiently to permit the wall 42 on the cam 41 to engage behind the latch 44, and then returning the frame 94 to lowered position.

When the auxiliary ribbon is in position to write upon the record-sheet, it will be interposed between the back of the check and

the face of the record-sheet, and will therefore make impressions not only on the face of the record-sheet but on the back of the check, as well. This fact is important because the writing on the back of the check serves to protect it against alteration. To alter the check it would be necessary to erase the written characters at the same point on the front and back of it. This would make a very thin place in the check which could be easily detected. The new characters could not be substituted on both the front and back of the check to resemble those erased except by the use of a special machine, such as that disclosed in this application.

Variations may be resorted to within the scope of the invention, and portions of the improvements may be used without others.

Having thus described my invention, I claim:

1. In a typewriting machine, a ribbon for writing upon an outside sheet, an auxiliary ribbon for writing upon an inside sheet, means for maintaining the auxiliary ribbon in operative or inoperative position during writing operations, a paper-releasing handle, and means operating as an incident of the movement of the paper-releasing handle for moving the auxiliary ribbon to operative position.

2. In a typewriting machine, a ribbon for writing upon an outside sheet, an auxiliary ribbon for writing upon an inside sheet, mechanism for maintaining the auxiliary ribbon in inoperative position, a paper-releasing handle, and means moved into position by the paper-releasing handle to engage said mechanism and render it ineffective.

3. In a typewriting machine, a ribbon for writing upon an outside sheet, an auxiliary ribbon for writing upon an inside sheet, a frame carrying the auxiliary ribbon comprising a shaft and a pair of plates fixed thereto, a spring connected to the shaft and urging it in a direction to lower the auxiliary ribbon to operative position, a cam on the shaft, and a latch co-operating with the cam to resist the spring and retain the auxiliary ribbon in inoperative position.

4. In a typewriting machine, a ribbon for writing upon an outside sheet, an auxiliary ribbon for writing upon an inside sheet, a frame carrying the auxiliary ribbon, a spring urging the frame in a direction to move the auxiliary ribbon to operative position, a latch for preventing such movement, a hook pivoted on the latch, a paper-releasing handle, and means moved into engagement with the hook by movement of the paper-releasing handle in one direction and movable to draw the hook downwardly and thereby swing the latch by movement of the paper-releasing handle in the other direction.

5. In a typewriting machine, a ribbon for writing upon an outside sheet, an auxiliary ribbon for writing upon an inside sheet, a frame carrying the auxiliary ribbon, a spring urging the frame in a direction to move the auxiliary ribbon to operative position, a latch for preventing such movement, a hook pivoted on the latch, feed-roller releasing mechanism comprising a link, and a beak on said link arranged to swing the hook aside when the link is raised and to engage the hook and draw it downward to release the latch when the link is depressed.

6. In a typewriting machine, a platen-frame, ribbon mechanism mounted on the platen-frame and movable therewith, a feed-roller cast-off finger-piece, a detent for maintaining the ribbon in a raised inoperative position, and means rendered effective by an operation of the feed-roller cast-off finger-piece to lower the ribbon to operative position.

7. In a typewriting machine, a ribbon for writing upon an outside sheet, an auxiliary ribbon for writing upon an inside sheet, and means operating as an incident of the line-spacing of the work for moving the auxiliary ribbon to inoperative position.

8. In a typewriting machine including a platen and a line-spacing mechanism, a ribbon for typing upon an outer sheet, a displaceable auxiliary ribbon for manifolding upon an under sheet, and means dependent upon the line-spacing mechanism for automatically displacing the auxiliary ribbon to an inoperative position.

9. In a typewriting machine, a ribbon for writing upon an outside sheet, an auxiliary ribbon for writing upon an inside sheet, a platen, mechanism for line-spacing the platen, and means movable by the line-spacing mechanism to move the auxiliary ribbon to an inoperative position.

10. In a typewriting machine, a platen, a platen-frame, a shaft mounted on the platen-frame parallel to the platen, ribbon-carrying mechanism mounted on the shaft, mechanism for line-spacing the platen, and means moved by the line-spacing mechanism for rocking the ribbon-carrying mechanism upwardly about the axis of the shaft.

11. In a typewriting machine having a platen and mechanism for line-spacing the platen, a ribbon for writing upon an outside sheet, an auxiliary ribbon for writing upon an inside sheet, and means operated by the line-spacing mechanism for rendering the auxiliary ribbon inoperative.

12. In a typewriting machine, a ribbon for typing upon an outer sheet, a displaceable auxiliary ribbon to manifold upon an inside sheet, a vibratory frame carrying the auxiliary ribbon, line-spacing mechanism for feeding both work-sheets a line-space distance to condition the outer sheet for the

next line of typing, means operated by the line-spacing mechanism for simultaneously displacing the auxiliary ribbon to an inoperative position, and means to hold the auxiliary ribbon in the inoperative position after the line-space mechanism has been restored to normal position.

13. In a typewriting machine having a platen and mechanism for line-spacing the platen, a ribbon-carrying frame mounted for swinging movement, a pin on the ribbon-carrying frame, and a cam movable by the line-spacing mechanism for engaging the pin and moving it to swing the ribbon-carrying frame.

14. In a typewriting machine having a platen and mechanism for line-spacing the platen, a ribbon for writing upon an outside sheet, an auxiliary ribbon for writing upon an inside sheet, a slide connected to the line-spacing mechanism having a cam thereon, and means movable by the cam to move the auxiliary ribbon to inoperative position.

15. In a typewriting machine having a platen, a ribbon for writing upon an outside sheet, an auxiliary ribbon for writing upon an inside sheet, a frame carrying the auxiliary ribbon, line-spacing mechanism comprising a slide movable horizontally a uniform distance in all line-spacing operations, and a cam moved by the slide, said cam having a beveled upper face for engaging the auxiliary ribbon-carrying frame and lifting it a uniform distance at each line-spacing operation.

16. In a typewriting machine, a ribbon for writing upon an outside sheet, an auxiliary ribbon for writing upon an inside sheet, a platen, mechanism for line-spacing the platen, a platen-frame, a shaft mounted on the platen-frame parallel to the platen, auxiliary ribbon carrying and guiding plates fixed to the shaft near its opposite ends, a cam on the shaft having a radially-extending wall thereon, means operated by the line-spacing mechanism for lifting the auxiliary ribbon carrying and guiding plates and rocking the shaft, and a latch for engaging the radial wall of the cam on the shaft to lock it in the position to which it has been rocked.

17. In a typewriting machine having a platen, mechanism for line-spacing the platen, a ribbon for writing upon an outside sheet, an auxiliary ribbon for writing upon an inside sheet, a frame carrying the auxiliary ribbon, a cam-slide movable by the line-spacing mechanism to raise the auxiliary ribbon-carrying frame, a latch for retaining the frame in raised position, and a spring for returning the cam-slide to normal position.

18. In a typewriting machine having a platen and mechanism for line-spacing the

- 6
- platen, a ribbon for writing upon an outside sheet, an auxiliary ribbon for writing upon an inside sheet, means operated by the line-spacing mechanism for lifting the auxiliary ribbon to an inoperative position, means for latching it in said position, and means for returning it to an operative position.
19. In a typewriting machine, a ribbon for typing upon an outer sheet, a displaceable auxiliary ribbon for manifolding upon an inner sheet, means for maintaining the auxiliary ribbon at operative and inoperative positions during the course of writing, line-spacing mechanism connected to displace the auxiliary ribbon, and means for typing a two-line entry upon one work-sheet and a single-line entry upon the inner work-sheet.
20. In a typewriting machine having a platen and mechanism for line-spacing the platen, a ribbon for writing upon an outside sheet, an auxiliary ribbon for writing upon an inside sheet, a paper-releasing handle, means operated by the line-spacing mechanism for rendering the auxiliary ribbon inoperative, and means operated by the paper-releasing handle for rendering the auxiliary ribbon operative.
21. In a typewriting machine having a platen, line-spacing mechanism, and a paper-releasing handle, a ribbon for writing upon an outside sheet, an auxiliary ribbon for writing upon an inside sheet, a frame carrying the auxiliary ribbon, means operated by the line-spacing mechanism for raising the auxiliary ribbon-carrying frame, a latch for retaining the frame in raised position, means operated by the paper-releasing handle for rendering the latch ineffective, and a spring for returning the auxiliary ribbon-carrying frame to lowered position.
22. In a typewriting machine having a platen, mechanism for line-spacing the platen, and a paper-releasing handle, a ribbon for writing upon an outside sheet, an auxiliary ribbon for writing upon an inside sheet, a frame carrying the auxiliary ribbon, a pin on the auxiliary ribbon-carrying frame, a cam having a horizontal surface on which the pin rests when the auxiliary ribbon is in operative position and an inclined portion for raising the auxiliary ribbon-carrying frame to move the auxiliary ribbon to inoperative position when the cam is moved horizontally, connections between the line-spacing mechanism and the cam for moving the cam rearwardly, a latch for automatically retaining the auxiliary ribbon-carrying frame in the position to which it is raised by the cam, means operable by the paper-releasing handle to withdraw the latch, and means for returning the auxiliary ribbon-carrying frame to restore the auxiliary ribbon to operative position.
23. In a typewriting machine including paper-feeding and line-spacing elements, a ribbon for typing upon an outer sheet, an auxiliary ribbon for manifolding upon an under sheet, means operable by the paper-feeding elements after gaging the outer sheet to the first line position thereon, to simultaneously set the auxiliary ribbon to manifolding position, and means operated by the line-spacing elements to line-space both sheets and shift the auxiliary ribbon to an inoperative position during the typing of the second line on the outer sheet.
24. In a typewriting machine including paper-feeding and line-spacing elements, a ribbon for typing upon an outer sheet, an auxiliary ribbon for manifolding upon an under sheet, means operable by the paper-feeding elements after gaging the outer sheet to the first line position thereon, to simultaneously set the auxiliary ribbon to manifolding position, means operated by the line-spacing elements to line-space both sheets and shift the auxiliary ribbon to an inoperative position, and means for retaining the auxiliary ribbon in the inoperative position during the typing of the second line on the outer sheet.
25. In a typewriting machine including paper-feeding and line-spacing elements, a ribbon for typing upon detached outer sheets, an auxiliary ribbon for manifolding upon a continuous record-sheet, and means operated automatically by the line-spacing elements for causing the auxiliary ribbon to become operative or inoperative, respectively, during the typing of alternate lines upon the outer sheets.
26. In a typewriting machine, a ribbon for writing upon an outside sheet, an auxiliary ribbon for writing upon an inside sheet, means for moving the auxiliary ribbon to inoperative position, and means operating during movement of the auxiliary ribbon to inoperative position to feed the auxiliary ribbon.
27. In a typewriting machine, a ribbon for writing upon an outside sheet, an auxiliary ribbon for writing upon an inside sheet, a frame on which the auxiliary ribbon is mounted, means for moving the frame to locate the auxiliary ribbon in an inoperative position, and means operated by such movement of the frame to feed the auxiliary ribbon.
28. In a typewriting machine having a platen and mechanism for line-spacing the platen, a ribbon for writing upon an outside sheet, an auxiliary ribbon for writing upon an inside sheet, a frame on which the auxiliary ribbon is mounted, operating connections between the line-spacing mecha-

nism and the frame for raising the frame when the line-spacing mechanism is operated, and mechanism operated by the movement of the frame to feed the auxiliary ribbon.

29. In a typewriting machine, a ribbon-carrying frame mounted for swinging movement, a ribbon-carrying spool rotatably mounted on the frame, a ratchet-wheel bearing fixed relation to the spool, a line-spacing lever, means operated by the line-spacing lever for rocking the swinging frame, and means for engaging the ratchet-wheel to rotate it relatively to the frame during such swinging movement of the frame.

30. In a typewriting machine, a ribbon-carrying frame mounted for swinging movement, a line-spacing lever, a slide moved horizontally by said lever, a cam on the slide for swinging the ribbon-carrying frame, and mechanism becoming effective as an incident of the swinging of the ribbon-carrying frame to feed the ribbon.

31. In a typewriting machine, a platen-frame, a platen, a shaft mounted in the platen-frame parallel to the platen, plates fixed on the shaft, ribbon-spools carried by the plates, mechanism for rocking the shaft, and means for rotating one of the ribbon-spools when the shaft is rocked.

32. In a typewriting machine, a platen-frame, a platen, a shaft mounted in the platen-frame parallel to the platen, plates fixed on the shaft, ribbon-spools rotatably carried by the plates, ratchet-wheels mounted on the plates for unitary movement with the ribbon-spools, means for rocking the plates to move the ribbon-spools and ratchet-wheels bodily, pawls on the platen-frame for engaging the respective ratchet-wheels to cause them to rotate relatively to the plates when the plates are rocked, and means for preventing operative engagement of more than one of the pawls at a time with its ratchet-wheel.

33. In a typewriting machine, a pair of ribbon-spools, a ratchet-wheel fixed to each ribbon-spool, means for moving the ribbon-spools and ratchet-wheels bodily in unison, means for engaging the respective ratchet-wheels to cause them to rotate relatively to their supports when they are moved bodily, and mechanism for controlling the ratchet-wheel-engaging means to render them alternatively operative.

34. In a typewriting machine, a pair of ribbon-spools, mechanisms for rotating the spools to feed the ribbon in opposite directions, levers for engaging the feeding mechanisms of the respective spools and moving them to inoperative positions, a shaft extending across the machine, angularly related crank arms on the shaft, the tails of the levers having cams upon them arranged for engagement by the crank arms, the ar-

angement of the crank arms and cams being such that when either of the levers is held in position to render its ribbon-feeding mechanism inoperative the other feeding mechanism will be permitted to occupy its operative position.

35. In a typewriting machine, the combination with a platen and types, of an inking ribbon whereby upon each of a succession of checks a payee line may be typed, with the amount of the check on the same line in figures, and whereby upon a succeeding line the amount of the check may be spelled out, means for causing the payee line to be typed concomitantly upon a record-sheet at single line-space intervals, including an inking ribbon interposed between the check and the record-sheet, whereby the payee line is manifolded upon the record-sheet, means to line-space the platen together with the check and record-sheet, means effective at the line-spacing operation for silencing said interposed ribbon, whereby a blank line is left upon the record-sheet at the operation of spelling out the amount upon the check, releasable means to hold both sheets against the platen, means for holding the record-sheet stationary while the released check is removed and a fresh check substituted with its payee line in typing position, and means for automatically restoring said interposed ribbon to effective position preparatory to manifolding the payee line of the second check in said blank space left upon said record-sheet at the typing of the first check.

36. In a typewriting machine, a platen, a platen-frame, a ribbon-carrying frame comprising a rock-shaft mounted in the platen-frame and plates fixed to the rock-shaft, ribbon-spools mounted on the plates for rotation about axes parallel to the platen, means on the plates for guiding the ribbon downward from the spools and horizontally across the machine, and means for swinging the ribbon-carrying frame to carry the ribbon and spools as a unit from operative position to an inoperative position just above and behind the printing point without interrupting typing on an outside sheet, where it may remain between said sheet and an inner sheet during farther typing on the outside sheet.

37. In a typewriting machine, a platen, a platen-frame, a shaft mounted in the platen-frame parallel to the platen, plates extending forwardly from the shaft having laterally bent portions provided with inclined slots and forwardly bent portions provided with vertical slots, ribbon-spools mounted on the plates, anti-friction means mounted on the plates for guiding the ribbon between the ribbon-spools and the inclined slots, and means for raising the plates as a unit to locate the ribbon in an inoperative position.

just above and behind the printing point without interrupting typing on an outside sheet, where it may remain between said sheet and an inner sheet during farther typing on the outside sheet.

38. In a typewriting machine, a platen, a platen-frame, a shaft mounted in the platen-frame parallel to the platen, plates fixed on the shaft and extending forwardly therefrom, laterally-bent portions of the plates provided with inclined slots and forwardly-bent portions provided with vertical slots, ribbon-spools mounted on the plates for a free rotation about axes parallel to the platen, means for raising the plates and spools to raise the ribbon to an inoperative position, means to promote a rotation of either spool during the upward movement of the spools, and retarding means to check the free rotation of both spools to keep the ribbon taut.

39. In a typewriting machine, a platen, a platen-frame, a shaft mounted in the platen-frame parallel to the platen, plates fixed on the shaft and extending forwardly therefrom, laterally-bent portions of the plates provided with inclined slots and forwardly-bent portions provided with vertical slots, ribbon-spools mounted on the plates for a free rotation about axes parallel to the platen, means for raising the plates and spools to raise the ribbon to an inoperative position, means to promote a rotation of either spool during the upward movement of the plates, retarding means to check the free rotation of both spools to keep the ribbon taut, and means for reversing the direction of the ribbon-feed.

40. In a typewriting machine having a platen, a pair of ribbon-spools mounted at opposite ends of the platen for rotation about axes parallel to the platen, means for rotating the spools to feed the ribbon, means for guiding the ribbon down from the spools and then laterally of the machine, mechanism for lifting the ribbon-spools and ribbon-guiding means as a unit to move the ribbon to an inoperative position just above and behind the line of writing, and means for keeping the ribbon taut.

41. In a typewriting machine, a platen-frame, a ribbon-carrying frame comprising a shaft extending across the platen-frame, a paper-positioning frame mounted for rotation on the shaft, means for turning the paper-positioning frame about the shaft to raise it out of operative position, and co-acting means on the paper-positioning frame and ribbon-carrying frame to cause the ribbon-carrying frame to be raised in unison with the paper-positioning frame throughout a portion of the swinging movement thereof.

42. In a typewriting machine, a platen-frame, a ribbon-carrying frame comprising a shaft extending across the platen-frame, a

paper-positioning frame mounted for rotation on the shaft, means for rotating the paper-positioning frame, pins on the paper-positioning frame, and pins on the shaft arranged to be engaged by the pins on the paper-positioning frame to cause the shaft to rotate in unison therewith.

43. In a typewriting machine, a platen-frame, a ribbon-carrying frame comprising a shaft and plates rigidly connected thereto, said shaft extending across the platen-frame, means for swinging the ribbon-carrying frame to operative position and to a normal inoperative position, a paper-positioning frame mounted on the shaft for swinging movement to position it out of the way during the insertion of a sheet in the machine, and means on the paper-positioning frame for engaging the ribbon-carrying frame and moving it to a position more remote from operative position than the inoperative position to which it is normally moved.

44. In a typewriting machine, a platen, mechanism for line-spacing the platen, a ribbon for writing upon an outside sheet, an auxiliary ribbon for writing upon an inside sheet, means operated by the line-spacing mechanism for moving the auxiliary ribbon to an inoperative position, and other means operable at the will of the operator for moving the auxiliary ribbon to inoperative position.

45. In a typewriting machine, a platen, mechanism for line-spacing the platen, a ribbon for writing upon an outside sheet, an auxiliary ribbon for writing upon an inside sheet, means operated by the line-spacing mechanism for moving the auxiliary ribbon to withdraw it to an inoperative position, means for moving the auxiliary ribbon to a position more remote from operative position than the position to which it is moved by actuation of the line-spacing mechanism, and means for retaining the auxiliary ribbon in either of its withdrawn positions.

46. In a typewriting machine, a platen, mechanism for line-spacing the platen, a ribbon for writing upon an outside sheet, an auxiliary ribbon for writing upon an inside sheet, a frame carrying the auxiliary ribbon, means operated by the line-spacing mechanism for moving the auxiliary ribbon-carrying frame to withdraw the auxiliary ribbon to an inoperative position, additional means for moving the auxiliary ribbon-carrying frame to withdraw the auxiliary ribbon to the same inoperative position without actuating the line-spacing mechanism, and means for locking the auxiliary ribbon-carrying frame in said inoperative position.

47. In a typewriting machine, a platen, feed-rollers co-operating therewith, a paper-releasing handle controlling the operative condition of the feed-rollers, a ribbon for

writing upon an outside sheet, an auxiliary ribbon for writing upon an inside sheet, a frame carrying the auxiliary ribbon, a spring urging the frame toward operative position, means for locking the frame in position to maintain the auxiliary ribbon in inoperative position, means operated by the paper-releasing handle to release said locking means, and additional means operable 10 to release said locking means.

48. In a typewriting machine, a platen-frame, a platen, a plurality of separate means for rotating the platen to line-space the work, a ribbon for writing upon an outside sheet, an auxiliary ribbon for writing upon an inside sheet, a frame carrying the auxiliary ribbon, and means operated by one only of the line-spacing means to lift the auxiliary ribbon-carrying frame.

20 49. In a typewriting machine, a platen-frame, a platen, a ribbon for writing upon an outside sheet, an auxiliary ribbon for writing upon an inside sheet, a frame carrying the auxiliary ribbon, means for rotating the platen to line-space the work, means operated by the line-spacing means to raise the auxiliary ribbon-carrying frame, additional means for rotating the platen to line-space the work without raising the auxiliary 25 ribbon-carrying frame, and means for raising the auxiliary ribbon-carrying frame without rotating the platen.

50. In a typewriting machine, a ribbon for typing on an outside sheet, an auxiliary ribbon for manifolding upon an inside sheet, and arranged to be effective during the typing of one line only on the outer sheet, mechanism to feed both sheets a line-space distance, and means operated automatically 30 with the line-space movement to feed the ribbon and render it ineffective to manifold

after each line in which it is used and to remain ineffective during further typing of the outer sheet.

51. In a typewriting machine, a platen, a 45 swinging paper-guiding frame comprising a plate for gaging the leading edge of an outside sheet and a roller carried by the frame and resting on the platen for clamping and feeding an inside sheet and controlling the effective position of the gaging plate, and a handle for swinging the frame to withdraw it from the platen to permit the inside sheet to be inserted in the machine without obstruction.

55 52. In a typewriting machine, a platen, a swinging paper-guiding frame comprising a plate on the frame having flanges for gaging an outside sheet, means for adjusting the plate laterally and vertically on the frame, 60 a roller carried by the frame and resting on the platen for guiding an inside sheet and controlling the effective position of the plate, and a handle for swinging the paper-guiding frame to withdraw the plate and roller 65 from the platen.

53. In a typewriting machine, a platen, a ribbon-carrying frame, a ribbon carried by the frame and normally held in proximity to the front of the platen, a swinging paper-guiding frame comprising a plate for gaging an outside sheet and a roller resting on the platen for guiding an inside sheet, a handle for swinging the paper-guiding frame to withdraw the plate and roller from 70 the platen, and co-acting means on the ribbon-carrying frame and the paper-guiding frame arranged to cause the ribbon to be withdrawn from the platen by the swinging of the paper-guiding frame.
